FIG. 5.

INVENTOR.

James Kelly.

By Charles P. Hannigan,
Attorney.

UNITED STATES PATENT OFFICE.

JAMES KELLY, OF PROVIDENCE, RHODE ISLAND.

AIR COOLING AND HUMIDIFYING APPARATUS.

No. 890,516.

Specification of Letters Patent.

Patented June 9, 1908.

Application filed October 23, 1907. Serial No. 398,847.

To all whom it may concern:

Be it known that I, JAMES KELLY, a citizen of the United States, residing at the city of Providence, county of Providence, State 5 of Rhode Island, have invented certain new and useful Improvements in Air Cooling and Humidifying Apparatus, of which the following is a specification.

My invention relates to an air cooling and humidifying apparatus, and is an improvement upon the apparatus shown and described in Letters-Patent of the United States, No. 787,454, issued to me April 18, 1905, and is designed generally to perform 15 the same functions, but embodies novel features of construction and operation adapted to perform the desired functions in a more perfect manner than are performed by the apparatus of the patent.

My present invention aims to provide an improved apparatus for use in supplying moisture to the atmosphere of cotton-mills, factories, and the like and wherever it is desirable to artificially moisten the atmosphere.

Still further objects of my present invention are to provide a novel filtering structure arranged to permit of ready removal of filter parts, means to regulate the supply of water and air to the filters, and means to regulate 30 the flow of water from the filter, whereby a perfect discharge of either a hot or cold vapor for the distributor may be effected.

This apparatus is especially adapted for the rooms of mills, wherein the air is liable to become very dry or full of dust of fibers in consequence of the employment of manufacturing processes, which are detrimental to the health or comfort of the workmen.

In the accompanying sheet of drawings, 40 Figure 1 represents a side elevation of my improved air cooling and humidifying apparatus, as secured in operative position on the ceiling of a mill-room. Fig. 2 is an enlarged central longitudinal sectional view 45 of the body of the apparatus, illustrating the parts embodying my improvement. Fig. 3 is a sectional view taken in line 3.—3. of Fig. 2, showing a sprocket wheel for operating the shut-off cocks of the apparatus. 50 Fig. 4 is a top plan sectional view taken in line 4.—4. of Fig. 2, showing one of the improved filters as mounted within the body of the apparatus. Fig. 5 is a side elevation of 55 the filter-frame and a portion of its wire screen mounted thereon. Fig. 6 is a vertical

sectional view of the distributor, and, Fig. 7 is a top plan view taken in line 7.—7. of Fig. 6.

Like reference characters indicate like parts.

The body of my improved apparatus is in the form of a casting A adapted to be secured to the ceiling of a mill-room, by bolts a, a, and this body of the apparatus has tubular portions b and c, which provide respectively water and air passages. These tubular portions curve over each other and have their lower ends screw-threaded to engage with shut-off cocks of the apparatus. The upper ends of these tubular portions b and c terminate at the center of cylinders d and e, which are each arranged to receive a filter. Each tubular portion b and c is in open communication with the interior of each cylinder d and e, and beyond each cylinder and centrally thereof, is arranged a head f and a tube g, and between said head and said tube is a vertical extension h, which is provided with a small water duct or port i.

My improved filters are constructed alike and of equal size, and each filter comprises a frame made of tin or other suitable light material, said frame having a closed body portion j integral with outer longitudinally arranged strips j¹, j¹ to contact upon the peripheral surface of the cylinders, and on this frame and strips is secured layers of wire gauze k.

Each filter, as described, is in the form of a five-pointed star, in cross-section, as shown, and each filter is secured within each cylinder d, e, by a cap l which is provided with a screw-threaded portion to engage thereby with the threaded open end of each cylinder, in the manner shown in Fig. 4. The body portion j of each filter-frame is provided with a small opening m for the reception of a hook or other suitable instrument to withdraw the filter from position, whenever the latter has to be cleaned from sediment.

In the head f of the body A is mounted a tubular support n. A needle-valve-stem o is movable in the head f, and said stem has a conical point o¹, which acts as a valve to bear against in closing a seat o² of a duct or port p communicating with the chamber of the water-filter. The valve-stem o is provided with a fine screw-threaded portion o³ to engage thereby with the threaded interior of the tubular support n, which is secured in the head f of the body A. Beyond the valve o¹ of the stem o, and centrally of the duct or

port i in the vertical extension h , is formed a circular recess to receive a washer q of felt or other suitable absorbent material. This washer is located below the needle-valve o^1 , and above said valve is secured a plug r , made to fit the opening required to form the recess for the washer q and duct i .

Shut-off cocks s, s , which are mounted on the lower ends of the tubular portions b and c of the body A , have their valve stems s^1, s^1 arranged in longitudinal alinement with each other, and each stem has its outer portion made flat, as at s^2, s^2 in Figs. 2 and 3, and on these flattened portions of the stems is secured a divided sprocket wheel t by bolts u, u . An endless chain v is mounted on the wheel t and of a length to come within easy reach to be pulled upon in regulating the opening or closing of the cocks. A sprocket wheel w is secured upon the outer end of the needle-valve-stem o , and this wheel is also provided with an endless chain x to operate the needle-valve. Branch pipes y, y connect with the cocks s, s , and from the tube g of the body A , a pipe y^1 leads to the vapor-distributer z .

The operation of the apparatus is as follows: Referring to Fig. 2, a pull upon the chain v , of the sprocket t , opens both cocks simultaneously, and permits the water and air to pass through the passages b and c of the body A and through the screens k, k of the filters. The valve o^1 is moved slightly from its seat, by means of the chain connection x with the sprocket w , and as the water leaves its filter, in the direction indicated by the arrow in Fig. 2, it passes through the duct or port p and percolates through the washer q , from whence the water falls in drops through the duct or port i . The water pressure is greater than the air pressure, consequently as the air passes through the tube g and meets with the drops of water from the port i they are brought together and co-mingled at this point, as g^1 in Fig. 2, and from this point the water and air is discharged in the form of a spray to pass through the pipe y^1 and out through the vapor-distributer z .

The washer q being of absorbent material aids to break the flow of water from the duct or port p , in order that the water may fall drop by drop through the duct or port i , and thereby to obtain the proper spray or vapor through the pipe y^1 and distributer z . The vapor-distributer z comprises a tubular member z^1 whose lower end is closed by a screw-threaded plug z^2 and its upper end having an enlarged cylindrical head z^3 disposed a circular bevel face z^4 , for the spray or vapor to contact upon, and a collar z^5 provided with a screw-threaded opening to engage the threaded end of the branch pipe y^1 , this opening being concentric with the bevel face of the tubular member, and said collar

having an integral annular flange z^6 made fast upon the circumferential surface of the head and provided with slotted openings z^7 which lead from the adjacent faces of said collar and said head and these openings of a size to leave narrow upright extensions z^8 for the vapor to pass between. The tubular member z^1 of the distributor, acts as a receptacle to receive any of the water which has for any reason not become subjected to the atomizing process, and this drip-cup may be readily drained by removing the plug z^2 .

By having the filters star-shaped in cross-section disposes a large area of screen surface to catch any foreign particles of dust or sediment that may pass through the cocks, and at the same time the arrangement of mounting the filters permits of their being easily removed for cleaning, by simply unscrewing the caps or covers l, l of the body A .

By regulating the needle-valve o^2 of the water supply, the spray or vapor can be made either heavy or fine as may be desired for the conditions existing in the room.

By my construction and arrangement of parts, I provide an apparatus which is not liable to get out of order, which is very easily taken apart, cleaned, and reassembled, and at the same time an apparatus that is comparatively cheap to manufacture.

What I claim and desire to secure by Letters-Patent, is—

1. In an air cooling and humidifying apparatus, the combination of a casting adapted to be secured to a ceiling and said casting having a water passage communicating with a water-cylinder and also an air passage communicating with an air-cylinder, and said casting having a duct leading from the water-cylinder and also a port communicating with an air-tube of the air-cylinder; a removable filter in each cylinder of the casting and each filter star-shaped in cross-section; a needle-valve arranged to close the duct of the water-cylinder; a washer of absorbent material beneath the valve of said needle and closing the port of said air-tube; shut-off cocks communicating with the water and air passages of said casting; a sprocket-wheel secured on the stems of said cocks; a sprocket-wheel secured on the stem of said needle-valve, and an endless chain mounted on each of said wheels.

2. In an air cooling and humidifying apparatus, the combination of a casting having a water supply and an air supply, said casting having a cylinder in open communication with the water supply and also a cylinder in open communication with the air supply, and said casting having a head-extension provided with a duct for the cylinder of the water supply and also a port in the extension of its head and communicating with the air-supply; a removable filter in each cylinder

- and each filter star-shaped in cross-section; means to secure each filter in the casting; a shut-off cock for the water supply; a shut-off cock for the air supply; means to simultaneously open or close both cocks; a needle-valve to seat against the water-duct of the casting; means to retard the water pressure between the duct and the port of the casting, and means to open or close said needle-valve.
- 10 3. In an air cooling and humidifying apparatus, the combination of a casting having a water supply and an air supply, a cylinder communicating with the water supply, a cylinder communicating with the air supply, and a head-extension provided with a duct to receive the water supply and also provided with a port communicating with the air supply, respectively; shut-off cocks; means to permit the cocks to open or close together in regulating the water and air supplies; a filter in each cylinder of the casting and each filter star-shaped in cross-section; a needle-valve arranged to check the flow from the duct of the casting; a washer made of absorbent material interposed between the valve of said needle and port of the casting; and means to regulate said valve.
- 15 4. In an air cooling and humidifying apparatus, the combination of the casting A having a water supply and an air supply respectively in open communication with cylinders
- 10 5. In an air cooling and humidifying apparatus, the combination of a head-extension tube *f*, *h*, *g*, the head being provided with a duct leading from the water cylinder and also a port through the head-extension and leading to the head-extension-tube; a filter for each cylinder and each filter comprising the frame *j* having a series of projecting strips *j'*, and wire gauze *k*, and each filter disposing a star-shaped structure in cross-section; the needle *o* arranged to close the duct; the washer *q* interposed between the duct and port; and the cocks *s*, *s*, provided with sprocket and pull-chain connection.
- 20 5. In an air cooling and humidifying apparatus, the combination of a vapor-distributor, comprising the tubular member *z*¹ having an enlarged head *z*³ disposing a bevel face, as *z*⁴, and the collar *z*⁵ provided with a threaded opening formed concentric to the face of the head and said collar having an integral annular flange *z*⁶ made fast upon the exterior surface of the head and provided with slotted openings *z*⁷ extending from the adjacent faces of both said members.
- 25 In testimony whereof I affix my signature in presence of two witnesses.

JAMES KELLY.
